UNITED STATES PATENT OFFICE.

JERVIS R. HARBECK, OF DETROIT, MICHIGAN, ASSIGNOR TO KEMIWELD CAN COMPANY, OF DETROIT, MICHIGAN, A CORPORATION OF MICHIGAN.

TUBE-MACHINE.

No. 862,390.

Specification of Letters Patent.

Patented Aug. 6, 1907.

Application filed November 8, 1906. Serial No. 342,471.

To all whom it may concern:

Be it known that I, JERVIS R. HARBECK, a citizen of the United States, and a resident of Detroit, in the county of Wayne and State of Michigan, have invented 5 a new and useful Tube-Machine, of which the following is a specification.

My invention relates to machines for forming tubes by convolutely winding strips of paper or other fibrous material coated with cement upon a mandrel, and the 10 object of my improvements is:—to provide a machine of this kind that shall be speedy and exact; that shall accurately wind a strip of glue covered material upon a mandrel and then slip the tube thus formed off the mandrel; and that shall be practically automatic in 15 its operation.

My invention consists in a novel hollow mandrel upon which the tube forming strip of paper may be wound, the mandrel being provided with lateral openings, over which the end of the strip is laid, so that 20 when the valve in a suction pipe of an air pump is opened, the strip of paper will be held on the mandrel.

My invention also consists of a novel automatic mechanism which winds the paper on the mandrel, cuts it off, rolls the end of the strip down, removes the 25 tube thus formed, and then feeds out a fresh length of paper of sufficient length to reach over the mandrel.

My invention further consists of novel mechanism for feeding the paper to the mandrel, which consists of a pair of rolls normally separated to permit the 30 mandrel to pull out as much paper as necessary, and in means to control the engagement of the rolls with the tube material so as to feed it to the mandrel.

My invention further consists in the novel details described in the following description and particularly 35 specified in the claims.

In the accompanying drawings, Figure 1 is a side view of the entire machine. Fig. 2 is a plan thereof, a portion of the paper support being broken away for the sake of clearness. Fig. 3 is a front view of the machine 40 on a somewhat larger scale. Fig. 4 is a side view of the tube-winding portion of the machinery on the same scale. Fig. 5 is a view from the opposite side of the cut-off mechanism, and Fig. 6 is a central cross section of the same. Fig. 7 is an end view of the main driving 45 cylinder. Fig. 8 is a side view of the same. Fig. 9 is a cross section of the same on the line 9—9 of Fig. 10. Fig. 10 is a plan of the same. Fig. 11 is a longitudinal section of the valve to control the air on the line 11—11 of Fig. 12. Fig. 12 is a vertical cross section of the same 50 on the line 12—12 of Fig. 11. Fig. 13 is a longitudinal cross section of the winding mandrel and sleeve. Fig. 14 is a cross section of the same on the line 14—14 of Fig. 13. Figs. 15, 16, and 21 are details of the paper feed. Figs. 17, 18, and 19 are details of winding man-

drels. Fig. 20 is a side view of the paper tension 55 device.

Similar reference characters refer to like parts throughout the several views.

This tube machine is made up of a main frame upon which may be supported a spool of paper or other material of which the tubes are to be made. The machine is composed of means to coat the strips of the tube material with glue or other cement; means to insure constant tension on the material and at the same time, prevent excess of tension; means to wind this strip 60 of material into a tube, and then discharge it from the machine; and means to feed this strip to the winding mechanism and to cut it off when the proper length has been wound.

The coating mechanism. The frame of the machine 70 is composed of bed 1 and the legs 2, the bed being of any desired height and preferably level. To the top are secured hangers 3, in which is mounted a shaft 4 to support the roll 5 of the material from which the tubes are to be made. Mounted on the bed is the mechanism 75 for coating the material with glue or other cement, and is built up of a receptacle 6 for the cement in which is mounted the large cylinder 7, which dips down into the liquid glue. This cylinder is mounted on the pivot screws 8 which pass through the walls of the receptacle. 80 A shaft 9 passes through lugs 10 at each end of the receptacle and on the ends of these shafts are secured the arms 11, which arms have rollers 12 mounted between their outer ends. The positions of the arms are determined by the set screws 13, as shown in Fig. 1. The 85 glue in the receptacle 6 may be kept hot by any desirable heating apparatus 14. In using this apparatus, the strip or band A of tube material passes upward from the roll 5 over the roller 15 carried by the shaft 16, that extends between the frames 17 on the bed 1. One 90 of these is omitted from Fig. 1. From here the band A passes to the rear over the cylinder 7 and in its movement turns this cylinder so that it will move through the glue and carry a thin uniform coat of it against the strip which is held against this cylinder 7, by 95 means of rollers 12.

The tension mechanism. The band A passes from the rear roll 12, between the feed rollers 18 and 19, down and around the roll 20 which is mounted on the shaft 21. This shaft is carried by the two chains 22 which pass 100 around the chain wheels 23 and 24. The paper passes from the roller 20 to the roller 25, loosely mounted on the shaft 26 and thence forward over the supporting platform or board 27 to the tube formed mechanism. In this machine, the paper passes to the tube forming 105 mechanism intermittently, and as the roll 5 of paper is often of great weight and inertia, it is necessary that a constant tension be applied to the strip of paper at the

- roll 15. It is also very desirable that the paper move through the glue applying mechanism at a constant rate. To insure these results, the following described mechanism is employed.
- 5 Projecting from the bed 1, are two frames 28 and 29 from which the brackets 30 and 31 project. In these brackets is mounted a shaft 32 on one end of which is a pulley 33. On this shaft is slidably mounted a friction wheel 34 which is adapted to engage a friction disk 35 secured to the shaft 36. This shaft is mounted in the frames 28 and 29 and carries a gear 37 which meshes with another gear 38, on the shaft 39. Auxiliary brackets 40 and 41 project upwards from the brackets 30 and 31 and in them is mounted a slidable rod 42 which carries a fork 43. The chain wheels 24 are secured to the shaft 26 which has a small gear 45 mounted on its outer end, which gear meshes with the rack 46 on the rod 42. The upper and lower rollers 18 and 19 are geared together at the end opposite the gear 38.
- 20 The operation of this mechanism is as follows. The weight of the roll 20 normally keeps it at the position shown in Fig. 20. The position of the friction wheel 34 will be controlled by the position of the roller 20. If too great a demand of the tube material occurs than can be supplied by the rollers 18 and 19, at their speed at that time, the roller 20 will be raised, which movement will move the chains 22 and with them the chain wheels 23 and 24. The revolution of the chain wheels 24 to the right, Fig. 20 will push the rod 42 to the left and with the rod the friction wheel 34 will be moved toward the center of the disk 35. The belt 48 on the pulley 33 has a constant speed given it by a counter shaft and therefore the friction wheel 34 has a constant speed. The speed of the friction disk 35 will therefore increase or decrease according as the wheel 34 moves toward and from the center of this disk. As before stated, the feed rollers 18 and 19 are driven by this friction disk 35, and their speed will therefore be increased by the rising of the roller 20 and be decreased by its falling. Any sudden increase in demand for tube material will be met by the roller 20 rising under the pull on the band A, which in turn will cause the feed rollers 18 and 19 to supply the extra demand. When the demand for material ceases entirely, the roller 20 will, of course, reach its lower position, when the friction wheel 34 will be entirely out of contact with the disk 35, as shown in Fig. 20. This particular part of the mechanism prevents the gummed face of the band A from reaching the floor because the feed rollers 18 and 19 will stop before such time and with them the movement of the band A. The paper as it leaves the tension mechanism, passes along over the table 27 and roller 50 with its coated side upward, to the shears, and from them to the winding mechanism.
- 55 *The winding mechanism.* Secured to the under side of the table are bearings for the driving shaft 51, which has on its outer end, tight and loose pulleys 52 and 53, and intermediate its ends, has mounted upon it a gear 54 which meshes with the gear 55 upon the main shaft 56. This main shaft 56 makes one revolution for each tube formed by the machine, and each revolution constitutes a complete cycle of operation of the machine. The steps taken by the mechanism at this end of the machine are as follows,—1st. The feed rollers extend a strip of paper to the mandrel. 2nd. The mandrel sucks

this paper to it and winds it upon itself the predetermined number of turns and then stops. 3rd. The shears cut the strip. 4th. The mandrel makes a predetermined number of revolutions during which time the paper on it is engaged by presser leaves for the purpose of insuring the gumming down of the end of the strip, whereupon the mandrel stops. 5th. A sleeve on the mandrel pushes off the completed tube. The mechanism for performing these various steps is controlled by the gear 55 and the drum 57.

The gear 55 has teeth extending entirely across its face for a portion only of its circumference, so that while it is constantly revolving under the action of the pinion 54, the pinion 58 which meshes with the gear 55, and the shaft 59 upon which this pinion is mounted, will have intermittent movement. In the machine shown in the drawings, this shaft 59 will have two periods of rotation;—during one of which it will make three turns and during the other, one turn, which periods will be spaced by rests. To insure complete stopping and starting of this shaft 59, the mechanism shown in detail in Figs. 7 to 10 inclusive, is employed.

As before stated, the teeth of the gear 55 extend entirely across its face for but a portion of the circumference, or stating it another way, the gear may be considered to be made up of two gears joined, one of which with teeth entirely around the circumference and the other with teeth in two separated groups, as shown in Fig. 9. The group 60 is designed to turn the mandrel to wind the strip of paper onto the same. While the space 61 is passing the pinion 58, the shears cut off the paper. The group of teeth 62 is designed to then turn the wheel 58 one revolution during which time the presser leaves smooth down the last end of the paper on the mandrel. The space 63 will pass the wheel 58 during the time that the sleeve on the mandrel pushes off the completed tube and during the time that the forward end of the tube material is fed forward to the mandrel.

The end of the drum 57 towards the gear 55 is formed with grooves or depressions which are adapted to receive the rollers 64 and 65, mounted on arms 66 and 67 secured to the outer end of the shaft 59. Referring to Fig. 9 especially and consider the shaft 59 at rest, and the drum 57 revolving toward the right, it will be noticed that the roller 65 has been traveling along in a groove 68 in the side of the drum, while the roller 64 has been riding upon the portion 69 of the face thus holding the shaft 59 stationary. When the rib 70 on the side of the drum strikes the roller 65, the shaft 59 will be set in motion and as the lever radius of the point of contact between the roller 65 and the rib 70 decreases, the shaft 59 will revolve more rapidly until finally the teeth of the gear 58 will travel at about the same speed as the teeth 60, when they engage the same. As will be seen in Fig. 9 the side of the drum is cut away immediately succeeding the rib 70 and up to the rib 71. The number of teeth of the pinion 58 and of the group of teeth 60 is such that the roller 65 will pass down into the groove or guide way 72, while the roller 64 will ride on the face at 73, thus holding the gear 58 and the shaft 59 stationary until the roller 65 contacts with the third rib 74, whereupon the arms 66 and 67 will again act to turn the shaft, and the group of teeth 62 will act to turn the shaft 59 one revolution. Next the roller 65 will

again enter the groove 68 and at the close of the revolution of the drum, all parts will be at the position shown in Fig. 9.

The shaft 59 is journaled in the standards 75 and 76, 5 and has secured to it the gear 77 which meshes with the gear 78 on the hollow shaft 79. This shaft is revolvably mounted in the standard 76 and also in the standard 80, and is adapted to revolve three times with each revolution of the shaft 59. Its outer end is provided 10 with a series of openings 80 (see Fig. 13), to connect the bore with the inside of the hollow mandrel 81 upon which the tubes are wound. This mandrel may have any desired cross section. The mandrel 81 is firmly secured on the hollow shaft 79, being held in place by 15 the screw 82, engaging in the end of the shaft. The end of the shaft 79 revolves in an elbow 83 which is supported by an arm 84 projecting from the standard 80. The pipe 85 connects to the valve 86 which is shown in details in Figs. 11 and 12. As there shown, the 20 shaft 56 has a longitudinal bore 87 and a vertical bore 88. A tube 89 connects this valve to the air pump 90 which is driven by the belt 91 from the same counter-shaft that drives the machine. It will be seen that the suction of the air pump will act through the pipes 89 25 and 85 and through the hollow shaft 79, the holes 80 in the same, and the holes 92 in the mandrel during the short time that the bore 88 in the shaft 56 registers with the bore of the pipe 85. The suction through the hole 92 in the mandrel will occur just at the beginning of the 30 winding revolutions of the mandrel, that is just about at the time that the parts are in the position shown in Fig. 9. The continued rotation of the shaft 56 will cause the strip of paper to be wound on the mandrel, the suction of the air pump holding the end of the paper 35 strip so firmly against the mandrel that the entire strip can be pulled along over the table 27 and around the tension device. This suction will continue during practically the entire time that the tube material is being wound on to the mandrel and ceases just before the 40 rotation of the shaft 79 ends.

The feeding and shearing mechanism. Mounted between the mandrel 81 and the frames 17 is the combined feed and cutting mechanism which is more clearly shown in Figs. 4, 5, and 6. On the base 95, which is secured to the bed 1, are adjustably mounted the side plates 96, which are connected by a cross bar 97. These parts 96 and 97 form a frame which is movable toward and from the mandrel, and because of the incline of the upper face of the base, the cutting line of the shears will 45 rise as the frame is moved away from the mandrel to accommodate tubes of larger diameters. Shafts 98 and 99 are geared together at their outer ends and carry rollers 100 and 101. As the upper roller 100 engages the coated side of the paper strip, it is preferably grooved 50 to facilitate disengagement from the sticky side of the paper, while the roller 101 is preferably of india rubber or similar elastic material to insure a good grip.

Secured to the shaft 56 is a cam 102 which is adapted 60 to act against the roller 103 on the side of the fork 104. A collar 105 also secured to the shaft 56 holds this fork in position. A sleeve 106 connected to the fork receives the connecting rod 107, pivoted on the pin 108 in the end of the lever 109. This lever is secured to one end of the shaft 110 upon which shaft are mounted two segmental gears 111, which engage the racks 112 on the

vertically movable rods 113. These rods are connected across by the lower member 114 of the shear, the upper member 115 being secured to the cross bar 97 of the frame. By these means at each revolution of the drum, the cam 102 will actuate the shear to cut off the 70 strip of paper.

Pivoted to the outer sides of the frames 96 are small levers 164, the outer ends of which are normally engaged by pins 165 on the upright rods 113, while the inner ends of the levers are under a portion of the bearings of the shaft 98 of the upper feed roll 100. Spring 116 extends between the lever 109 and the bed of the machine and normally holds down these rods and at the same time holds the rollers 100 and 101 apart. These feed rolls are normally separated in order to permit the 75 mandrel to wind up as much paper as necessary with the least amount of friction. Springs 116 tend to hold up the bearings of the shaft 98. It will be noticed that the cam 102 is of such form that during a portion of the revolution of the shaft 56, the rollers 100 and 101 will be 80 held separated by means of these springs which period corresponds to the winding of the tubes and that during the remainder of the revolution of the shaft 56, the rolls will be in contact with the paper.

The shafts 98 and 99 are geared together at the ends 85 shown in Fig. 4. On the opposite end of the shaft 99 is secured an arm 117 which carries a pawl 118 to engage the teeth of the ratchet wheel 119. This ratchet wheel is secured to a sleeve 120 loose on the shaft 99, to which sleeve is also secured a gear 121 which meshes 90 with a rack 122 (see Figs. 15 and 16). It will be seen that the reciprocating longitudinal movements of this rack 122 will cause a rotation in opposite directions of the gear 121 and the ratchet wheel 119 and the driving 95 in a constant direction of this roll 101 at each downwardly movement of the rack, the pawl 118 permitting the ratchet wheel to run freely in the opposite direction.

Mounted on the hub of the ratchet wheel 119 is the 100 guide 123 for the rack 122, which guide is adapted to 105 adjust itself to any angle to the vertical the rack may assume. See Figs. 5 and 16. The lower end of the rack connects to the arm 125 which is secured to the shaft 126. This shaft is mounted on bearings 127 beneath the bed and has at its inner end, a second arm 110 128 provided with a roller 129. At each revolution of the gear 55 a block 130, (see Fig. 4), secured to the gear, contacts with this roller 129, causing the shaft 126 to turn and the rack 122 to move downward, thereby 115 actuating the feed rollers. As the centers of movement 115 of the rollers 129 and the block 130 are separated, the contact of these two will last for about one twelfth of the revolution of the drum 57, and also that when the roller 129 and block 130 disengage, the spring 131 will return the rack to the position shown in Fig. 4. 120

The presser leaves. After the paper has been cut off it is necessary to give the mandrel a few turns in order to press down the end of the strip of tube material, for which purpose, the group of teeth 62 on the gear 55 are employed. On the bed are secured bearings 135 and 136 in which is mounted a shaft 137 provided with an arm 138. On the end of this arm is mounted a roller 139 which runs on a cam ring 140, secured to the side of the gear 55. This cam ring has one depressed portion shown at its upper side in Fig. 4. Mounted on the bed 130

is a frame 140, provided with horizontally extended arms 141 in which are mounted the presser leaves 142. These leaves are provided with rods 143 secured to lugs 144 formed on the leaves, between which rods springs 145 extend. Shoulders 146 are formed on the inner sides of these presser leaves and are adapted to be engaged by the roller 147 carried in the outer ends of the arms 148, which arms are secured to the shaft 137. The action of this portion of the machine is as follows. The 10 roller 147 is normally held between the shoulders 146 by the wheel 139 riding on the outer concentric portion of the ring 140. But immediately after the cam 102 has acted to operate the shears, and while the group of teeth 62 are driving the mandrel its second set of turns, the 15 depressed portion of the cam ring 140 will permit the wheel 139 to drop, causing the roll 147 to move from between the shoulders 146 and permitting the presser leaves 142 to close. The flat outer ends of the leaves will press on the tube wound on the mandrel and thus 20 insure the end of the paper being smoothly cemented down. When the cam 140 lifts the wheel 139, the leaves will separate.

Discharging mechanism. To remove the finished tube from the mandrel after the presser leaves operate 25 and again open, I provide a sleeve 150 which is slideable over the mandrel and on the hollow shaft 79. This sleeve is provided with a groove 151 in which a fork 152 is adapted to engage, (see Figs. 13 and 14). This fork is secured to a slideable rod 153 which is mounted 30 in the standards 76 and 80. Secured to this rod is a grooved collar 154 into which the upper end of the pivoted lever 155 is adapted to engage. The lower end of this lever is pivoted to a bracket 156 and the pin 157 is adapted to be engaged by the cams 158 and 159, 35 secured to the face of the drum 57. After the presser leaves have operated to insure the cement of the end of the paper strip to the remainder of the tube, the revolutions of the mandrel stop and the cam 158 will engage the pin 157, forcing over the lever 155 and also forcing 40 the sleeve 150 outward. The outward movement of the sleeve will push the tube of the mandrel. As it may very often happen, that the inner edge of this tube is sticky and therefore liable to attach itself to the outer edge of the sleeve 150, I provide springs 160 (see Fig. 45 8), which springs are adapted to be pressed inwardly by the tube as it passes over the same and spring out immediately after the tube has passed, thus preventing the tube being pulled back on to the mandrel by means of the sleeve. It will be noted that the cam 159 immediately returns the lever 155 and sleeve 150 to normal 50 position.

Operation of the machine. The operation of the machine is as follows,—The proper roll 5 of tube material having been selected, it is elevated to a position between the arms 3, and the shaft 4 passed through the same. The glue in the receptacle 6 having been properly heated, the band A is passed up over the roller 15 below the rollers 12 and over the cylinder 7 and on through between the feed rollers 18 and 19. The rollers 12 are 60 then adjusted so that the band A will be properly pressed against the cylinder 7. The band A is further unrolled and passed down around the roller 20 over the rollers 25 and 50 and forward between the feed rollers 100 and 101, and between the shears 114 and 115. 65 The machine is then set in motion. The belts from

the counter-shaft drive the air-pump 90, tight pulley 52 and shaft 51, and thereby the main gear 55 and drum 57, and also the pulley 33 and shaft 32. The first portion of the revolution of the drum will serve to actuate the arm 128, the shaft 126, the arm 125 and the 70 rack 122 to cause the feed rolls 100 and 101 to feed forward the paper strip so that the end will rest over the holes 92 in the mandrel. When this movement has been completed, the block 130 secured to the face of the gear 55 will disengage from the roller 129 permitting 75 the spring 131 to return these parts to the normal position. Just about the time that the roller 129 and the block 130 disengage, the shaft 56 will have reached such a position that the bores 87 and 88 in its inner end will open the passage from the air pump 90 80 to the bore of the shaft 79 and opening 92 into the mandrel, which will permit the suction of the pump to firmly hold the end of the paper against the mandrel. About this instant, the rib 70 on the end of the drum begins to operate the arms 67 on the shaft 59, whereupon the shaft 79 begins its nine revolutions. Just before the completion of these revolutions the rotation of the shaft 56 will be such that the passage from the pipe 89 to the pipe 85 will be closed. After the shaft 79 has stopped, the cam 102 will engage the roller 103 to 90 operate the shear and to cut off the paper. This occurs during the interval between the groups of teeth 60 and 62. When the teeth 62 cause the rotation of the mandrel, the arm 138 is falling because of the depressed portion of the cam ring 140 will permit the presser 95 leaves 142 to smooth down and insure the cementing of the end of the band of the paper. The next movement will be to raise the arm 138 and the separation of the presser leaves 142 which is immediately followed by the longitudinal movement of the sleeve 150 to eject 10 the finished tube. The continued movement of the drum causes the cam strip 159 to return the sleeve 150 to its normal position, when all parts will await the next action of the feed rollers 100 and 101.

It is evident that the mandrel may be of any desired 10 cross section so as to make tubes of different forms. As many sides and angles may be given the tube as desired so long as no angle is reentrant. The presser leaves 142 will act equally well on the rectangular mandrel 81 (Fig. 19) having suction holes 92, as on 11 a round mandrel.

Having now explained my improvements, what I claim as my invention and desire to secure by Letters Patent is—

1. In a tube machine, the combination of a hollow shaft, 11 an air pump suction pipe connected thereto, a removable mandrel on the end of said shaft provided with an aperture to permit pneumatic clutching of the tube material, a sleeve slideable over the mandrel to remove the finished tube and means to prevent the reverse movement of the 12 tube.

2. In a tube machine, a mandrel for winding tubes, a shaft to drive the same, a pair of pivoted leaves adapted to press against the outer side of the tube to insure perfect winding, a pivoted arm to control the operation of the leaves, and a cam mounted on said shaft to actuate said arm whereby the leaves press against the tube during the final revolutions only of the winding.

3. In a tube machine, the combination of a mandrel for winding the tubes, a shear, a pair of feed rolls for conveying the end of the tube material from the shear to the mandrel, an arm on the end of the shaft of one of the rolls, a pawl carried thereby, a ratchet wheel adapted to

- be engaged by said pawl, a gear united to said ratchet wheel, said gear and ratchet wheel loosely mounted on said roll shaft, a rack adapted to reciprocate to actuate the rolls, an arm to operate the rack, and means to actuate said arm and rack during the time said mandrel is at rest.
4. In a tube machine, the combination of a mandrel for winding the tubes, a shear, a pair of feed rolls for conveying the end of the tube material from the shear and to actuate the mandrel before and between the operations of the rolls and the shear, and means to separate the rolls to permit the mandrel to freely pull the tube material through between the rolls.
5. In a tube machine, the combination of a hollow mandrel, an air pump connected thereto and adapted through its operation to cause the adhesion of the tube material to the mandrel, a main shaft for driving the various parts of the machine and controlling the action of the air pump, a feeding mechanism for projecting the tube material to the mandrel, means mounted on the main shaft for driving the mandrel two series of revolutions for each revolution of the shaft, the first series occurring for winding the tube directly after the operation of the feed rolls, a shear operated by said shaft to sever the tube material, means operated by said main shaft during the second series of revolutions of the mandrel to press down the last edge of the tube material, and then discharge, and means operated by the main shaft to remove the tube after the end of the second series of revolutions.
- 30 6. In a tube machine, the combination of a main driving shaft, a gear, a drum and cams mounted thereon, a mandrel to wind up the tubes, a feeding mechanism, a shear, means to coat the material with cement, means to press against the tube on the mandrel to insure the best action of the cement, a sleeve to remove the tube from the mandrel, and connections between the various parts and the cams, gear and drum on the main shaft, whereby at each revolution of the main shaft the feeding mechanism will project the tube material to the mandrel, and stop, the mandrel will then partially wind the tube and stop, the shear will sever the material, the mandrel will complete the winding of the tube and stop, pressing means will engage and disengage the tube during these revolutions, and the sleeve will push the finished tube off the mandrel.
- 45 7. In a tube machine, an air pump, a revolute hollow mandrel, a connection at one end of the mandrel, a pipe attached to said connection and connecting to said pump, and a valve in said pipe and a shaft for driving said mandrel which shaft enters said valve and controls the action of the air pump.
8. In a tube machine, the combination of a hollow mandrel, an air pump suction pipe connected thereto, said mandrel being provided with air inlets, a sleeve slidably over said mandrel to remove the finished tube, and means to prevent the reverse movement of the tube.
- 55 9. In a tube machine, the combination of a winding mandrel, means to remove the finished tube from the mandrel, and means to prevent the reverse movement of the tube.
10. In a tube machine, the combination of a winding mandrel, means to drive the same comprising a shaft which makes one complete revolution during the winding of a tube, a cam on said shaft, a presser adapted to engage the tube during the final winding revolutions, a spring for actuating said presser, connecting means between said presser and cam whereby said presser is permitted to operate during such final revolutions only.
11. In a tube machine, the combination of an air pump, a hollow winding mandrel having apertures through which the suction of the air pump may operate to hold the tube material firmly on the mandrel, a driving shaft, gears between the driving shaft and mandrel, a pipe extending between the air pump and mandrel, and a valve in said pipe, the end of said driving shaft extending into said valve and being bored so as to open and close the passage through said valve.
12. In a tube machine, the combination of a winding mandrel, a main shaft for driving the various parts of the machine, a feeding mechanism for projecting the tube material to the mandrel, means mounted on the main shaft for driving the mandrel two series of revolutions for each revolution of the shaft, a shear operated by the main shaft after the first series of revolution of the winding mandrel, and means operated after the second series of revolutions to remove the tube from the mandrel.
13. In a tube machine, the combination of a general driving mechanism, a mandrel to wind the tubes, a feeding mechanism, a shear, means to coat the material with cement, means to contact with the material on the mandrel to insure the desired action of the cement, means to remove the finished tube from the mandrel, and connections between the various parts and the general driving mechanism, whereby at each tube forming period the feeding mechanism will project the tube material to the mandrel and stop, the mandrel will partially wind the material and stop, the shear will sever the material, the mandrel will complete the winding of the tube and the finished tube will be pushed off the mandrel.
14. In a tube machine, the combination of a winding mandrel, a feeding mechanism for projecting the tube material to the mandrel at the beginning of each tube forming period, means for driving the mandrel a plurality of series of revolutions for each tube forming period, a shear operated after one series of revolutions of the winding mandrel to sever the tube material, and means to remove the tube from the mandrel.

In testimony whereof I have signed my name in the presence of two subscribing witnesses.

JERVIS R. HARBECK.
